(57) **CLAIM**

The ornamental design for a cap, as shown and described.

DESCRIPTION

FIG. 1 is a top front left perspective view of a cap showing the design;

FIG. 2 is a front elevation view thereof;

FIG. 3 is a top plan view thereof;

FIG. 4 is a right side elevation view thereof;

FIG. 5 is a rear elevation view thereof;

FIG. 6 is a bottom plan view thereof;

FIG. 7 is a left side elevation view thereof;

FIG. 8 is a top rear right perspective view thereof;

FIG. 9 is a bottom front left perspective view thereof; and,

FIG. 10 is a bottom right perspective view thereof.

Portions of the cap shown in broken lines form no part of the claimed design.
